ESCUTCHEON PLATE AND HANDLE
ASSEMBLYHenry F. Keil, Scarsdale, N. Y., assignor to
Francis Keil & Son, Inc., a corporation of New
York

Application February 27, 1933, Serial No. 658,698

4 Claims. (Cl. 16—125)

This invention relates to a lock construction and more particularly to the face plate of a lock and its associated parts as well as a method of assembling constructions of this general nature.

5 One of the objects of this invention is to provide a lock plate construction which will be simple, practical and of inexpensive manufacture. Another object is to provide a construction of the above character whose individual parts are 10 characterized by pronounced simplicity and whose parts may be assembled with ease. Another object is to provide a construction of the above character wherein several of the parts thereof coact in a reenforcing capacity to increase materially the strength of the entire structure. Another object is to provide a construction of the above character in which the several parts when 15 disassembled may be packed into a small space and accordingly shipped in a comparatively small and inexpensive carton. Another object is to produce a construction of the above character wherein in the total number of parts is reduced to a minimum, thus facilitating quick assembly. Another object is to produce a construction of the above 20 character which will be light and at the same time very strong. Another object is to produce a construction of the above character wherein many of the parts may be formed from sheet metal without sacrificing durability and strength. 25 Another object is to provide a method of assembly for a construction of the above character which may be practiced with ease and efficiency. Another object is to provide a method of the above character which may be practiced by those 30 having little experience in the art. Other objects will be in part obvious and in part pointed out hereinafter.

The invention accordingly consists in the features of construction, combinations of elements, 35 arrangements of parts and in the several steps and relation and order of each of the same to one or more of the others, all as will be illustratively described herein, and the scope of the application of which will be indicated in the following claims.

In the accompanying drawing in which is shown one of the various possible embodiments of my invention,

50 Figure 1 is a rear elevation of my lock plate structure as assembled, certain portions thereof being broken away;

55 Figure 2 is a vertical sectional perspective view taken substantially along the line 2—2 of Figure 1;

Figure 3 is a horizontal sectional view taken along the line 3—3 of Figure 1, and

Figure 4 is a perspective view of one of the parts comprising my invention.

Similar reference characters refer to similar parts throughout the several views of the drawing.

As conducive to a clearer understanding of certain features of this invention it might here be pointed out that constructions of this general 10 nature have been characterized by a pronounced complexity of structure and a large number of individual parts. Not only is this a decided inconvenience in assembling after shipment but, also, the great number of parts involves the necessity of a correspondingly high number of operations to manufacture the constructions. Furthermore such a large number of parts increases the difficulties of shipment and the possibility of losing one or more of the parts during shipment. 15 Further still, it has been found in practice that these constructions even though built from a large number of parts are weak in many respects and subject to damage while in use. One of the various objects of this invention is to provide a construction in which the several difficulties hereinabove mentioned as well as many others are successfully and practically overcome.

Referring now to Figure 2, I have shown a face plate generally indicated at 10 having a border flange 11 extending outwardly and rearwardly from the main plane thereof (Figure 1). As better shown in Figure 1, I prefer to provide an aperture 12 formed in the upper end of plate 10 and of suitable size for the reception of the key receiving portion of a lock structure. Secured to plate 10 in a manner to be described hereinafter is a handle generally indicated at 13 and plate 10 also has formed therein a series of screw holes generally indicated at 14 and preferably countersunk. Accordingly plate 10 may be positioned over the lock construction in a door or the like and secured in such position by screws passing through holes 14 so that handle 13 may be used for opening and closing the door, while the key 30 receiving portion of the lock is exposed through aperture 12 as described above.

Turning back to Figure 2, the opposite ends of handle 13 are preferably reduced to form a pair of studs 15 and 16. Suitable apertures 17 and 18 50 are formed in plate 10 so that studs 15 and 16 may extend therethrough and above the rear surface of the plate. Thus when studs 15 and 16 are in the position shown in Figure 2, the end portions 13a and 13b of handle 13 rest flush against 55

the front side of plate 10. Preferably formed on the opposite sides of studs 15 and 16 are pairs of slots 19 and 20 respectively, these slots being spaced from end portions 13a and 13b thus being immediately above the rear surface of the plate 10 when the parts are in the position shown in Figure 2.

Turning to Figure 4, there is shown a fastening part generally indicated at 21. Part 21 is preferably channel shaped thus having a pair of flanges 22 and 23 upon its opposite sides. Formed in the base portion of part 21 are two bottle shaped apertures generally indicated at 24 and 25. Thus apertures 24 and 25 comprise large portions 24a and 25a and neck portions 24b and 25b. The upper portion of part 21, as viewed in Figure 4, is narrower than the main body portion thereof thus to allow these portions 23a and 22a of flanges 22 and 23 to extend away from the base thereof a greater distance than do flanges 22 and 23 for the greater part of their length.

Accordingly when assembling this lock plate construction, handle 13 is placed in the position shown in Figure 2 so that studs 15 and 16 extend through apertures 17 and 18 and end portions 13a and 13b lie flush against the front face of plate 10. Next, fastening part 21 is placed over the studs so that the studs extend through portions 24a and 25a of apertures 24 and 25. Now when fastening part 21 is forced downwardly, as viewed in Figure 2, neck portions 24b and 25b of apertures 24 and 25 slide into interlocking engagement with slots 19 and 20 as better shown in Figures 1 and 3.

Accordingly by this simple operation which may be easily performed even without the assistance of tools, the handle 13 is securely attached to plate 10 with no possibility of accidental displacement. Furthermore, fastening part 21 acts as a reenforcing element between apertures 17 and 18 thus preventing any longitudinal buckling of the plate between these points. Further still, I prefer to have the outer edges of flanges 22 and 23 substantially in the same plane as the edges of border flange 11 of plate 10. Inasmuch as suitable spaces are provided in the door for studs 15 and 16 as well as flange portions 22a and 23a and their associated parts, the edges of border flange 11 and flanges 22 and 23 may rest flush against the door thus acting to reenforce plate 10 against any lateral buckling or bending.

As more clearly shown in Figures 2 and 4, the upper portion of fastening part 21 has formed therein an aperture 26 between flange portions 22a and 23a and in registry with an aperture 27 in face plate 10 when the parts are in the above-described assembled position. Extending through apertures 26 and 27 is a thumb lever generally indicated at 28. A pair of aligned holes 29 and 30 are provided in flange portions 22a and 23a (Figure 4) and extending therethrough and through thumb lever 28 is a pin 31 provided with a suitable cotter pin 32 for holding it in its assembled position. Accordingly thumb lever 28 pivots about pin 31 thus to actuate various parts of the lock construction by way of portion 28a which is in association with these parts. Furthermore, lever 28 when in position locks fastening part 21 in its downward or fastening position so that it cannot be accidentally displaced.

It will now become clear that I have provided a lock construction chiefly characterized by the simplicity of its construction and the unity of its various parts. For example, handle 13 may be

secured to plate 10 by the simple operation of slipping fastening part 21 into the position shown in Figures 1 and 2. After thumb lever 28 has been secured in position, the assembly is complete and not only are the parts locked into their normal positions but, also, they act in a reenforcing capacity to strengthen the plate 10. Also the number of individual parts required for this construction is very small thus making for easy and convenient shipment as well as ease of assembly.

Preferably plate 10 as well as part 21 is formed from a suitable sheet metal material. Thus these parts may be stamped or otherwise formed in a convenient and economical manner, and, due to the reenforcing action of part 21 (more particularly flanges 22 and 23) the total structure remains unusually strong although formed from a comparatively weak material.

It will thus be seen that I have provided a thoroughly practical and efficient construction in which the several objects hereinabove mentioned as well as many others are successfully and practically accomplished.

As many possible embodiments may be made of the mechanical features of the above invention and as the art herein described might be varied in various parts, all without departing from the scope of the invention, it is to be understood that all matter hereinabove set forth or shown in the accompanying drawing is to be interpreted as illustrative and not in a limiting sense.

I claim:

1. In a latch construction, in combination, an escutcheon plate having a flanged border adapted to rest against the surface of a door or the like, said plate having a pair of spaced apertures in substantial alignment, a handle having two reduced ends extending through said apertures, said ends having slots upon their opposite sides, a part having flanges upon its longitudinal sides and keyholes in substantial alignment with said ends, said part resting against the under face of said plate so that the narrow portions of said keyholes interfit with said slots, the edges of said flanges and said border being in substantially the same plane and hence rest against the surface of said door, thereby to hold said plate against distortion out of its plane by pushing forces exerted upon said handle, and a lock lever extending through said plate and said part and pivotally connected to said part, said lock lever in extending through said plate locking said part against longitudinal movement thereof and thus preventing disengagement of the narrow portions of said keyholes from said slots.

2. In a latch construction, in combination, an escutcheon plate having a hole, a handle several portions of which extend through said plate, said portions having slots formed on one side thereof, a fastening element having bottle shaped apertures the larger portions of which fit over said ends, said fastening element adapted to slide along said plate so that the neck portions of said apertures come into interfitting engagement with said slots, said element having a hole that is in registry with said first-mentioned hole when said element is slid into said interfitting engagement with said slots, and a lock lever extending through said registered holes and pivotally connected to said element, whereby said lever prevents movement of said fastening element out of interfitting engagement with said slots.

3. In a latch construction, in combination, an escutcheon plate having a hole therein and an aperture spaced therefrom, a handle resting against the front face of said plate and having a portion extending through said aperture, a part on the other face of said plate and having means whereby upon relative movement between said part and said portion of said handle said part interengages with said portion to prevent withdrawal of said handle from said plate and whereby said part is secured against said other face of said plate, and a latch lever supported by said part, said latch lever passing through said hole in said plate and thereby preventing relative movement between said part and said portion of said handle and thereby locking these elements against disengagement.

4. In a latch construction having a plate, a handle having its opposite ends extending through said plate, said ends having slots formed therein, and a part having two holes in substantial registry with said ends and adapted to fit over said ends, said holes being formed with narrow portions so that said part may slide into interlocking engagement with said slots in said ends, the combination therewith of means for locking said part against sliding relative to said plate in a direction to disengage said parts from said slots, said means comprising a latch lever passing through said plate and said part and pivotally connected to said part behind said plate whereby said plate prevents access to said pivotal construction and hence prevents disengagement of said part and said ends when said construction is in assembled relation.
